UNITED STATES PATENT OFFICE.

ANTON N. HORNUNG, OF LOS ANGELES, CALIFORNIA.

REFRIGERATOR.

Application filed January 4, 1926. Serial No. 79,089.

This invention is applicable to refrigerators of any size but is more particularly valuable in connection with refrigerators of the larger sizes, and objects of the invention are, 5 to prevent warm air pockets; to give the cold air currents the most effective direction; to make the most convenient and effective disposal of the water produced by the melting ice; to minimize accumulations of moisture 10 on the walls and other surfaces; to minimize the surfaces on which such accumulations are likely to occur; to make provision for draining the drip from such surfaces, and to provide a cheap, simple, easily handled and effective arrangement of drainage trays.

Simplicity and moderate cost are also objects of the invention.

An object is to provide a practical knock down large size refrigerator adapted to be 20 made in a factory and to be transported in pieces to the place of use and there set up at minimum cost of labor.

Another object is to make provision for 25 easily and conveniently cleaning the refrigerator throughout, so as to secure perfect sanitation.

Other objects, advantages and features of 30 invention may appear from the accompanying drawings, the subjoined detailed description and the appended claims.

The accompanying drawings illustrate the invention.

Figure 1 is a broken isometric view of a 35 refrigerator constructed in accordance with this invention.

Fig. 2 is an enlarged isometric view of one of the collecting drip trays.

Fig. 3 is an isometric view of the drip discharging drain tray.

40 Fig. 4 is a broken plan view omitting the refrigerator top and showing interior construction fragmentally.

Fig. 5 is a fragmental elevation in section on line x^6 , Figs. 4 and 6, omitting the ice 45 and looking toward the back wall.

Fig. 6 is a fragmental elevation in section on line x^6 , Figs. 4 and 5.

Fig. 6^a is a fragmental detail of the drip trap.

50 Fig. 7 is a fragmental elevation of the upper part of the refrigerator in section on line x^7 , Figs. 4 and 5.

Fig. 8 is a fragmental elevation in section on line x^8 , Fig. 4.

Fig. 9 is an isometric view of the pan detached.

Arrows at the section lines indicate the direction of sight.

The refrigerator body is constructed with walls a , b , c , and d , top e and floor f , enclosing an ice chamber 1 and a storage and cooling room 2, and is provided in one end with the usual ice door 3 and cooling and storage room door 3''. 4 indicates a front window, and 5 a front shelf at such window inside the storage and cooling room 2. The doors are appropriately hinged as at 6 and 7 and secured with appropriate latches as at 8 and 9.

The tops of the walls are reduced in thickness on their inner sides to form shoulders 10 to support the top e .

The walls are preferably constructed with outside and inside wooden panels g , h formed of tongued and grooved boards, preferably 75 flooring nailed to upright studding i , plates j and sills k forming chambers m filled with insulation n .

The ice chamber 1 is arranged above the cooling room 2 and is separated therefrom by the pan 11 above which is provided an ice 80 rack 12, upon which ice, not shown, is placed through the ice door 3 for the purpose of lowering the temperature of the cooling room.

The plates j are shown channeled along the inner top corners to form a seat p for the insulated top e which is constructed in a manner similar to that of the walls.

13 and 14 indicate supports below the pan 11, for arms and projections 15, 15' of drip 90 trays 16 that are arranged in pairs below cold air chutes 17, opening downwardly through the pan.

The drip trays slope downwardly toward a central vertical plane which is indicated by the section line x^5 — x^5 , in Fig. 6, and are provided at their lowest points with drain outlets 18 through which water that has dropped through the chutes 17 into the drip trays, may escape to a drain tray 19 that extends aslant in the central part of the refrigerator to receive the drip from said drain outlets; and said drain tray 19 is mounted aslant transversely of the refrigerator and is provided with a discharge outlet 20 that discharges through a trap 21, into a pipe 22 that leads through the rear refrigerator wall c into a sewer or other suitable drain, not shown.

The cold air chutes 17 open downward from the ice chamber 1 to the cooling room 2, and consist of four rectangularly shaped openings arranged in the angles of a cross member 24 and separated by the four limbs of the cross. The top edges of the limbs of the cross are beveled and the cross is covered by sheet metal as at 25 to form a pan having the chute openings 17. Said member 24 is below the level of the ice rack 12 and above the level of the trays 16, and the lower edges of the chutes form drip skirts 26 of sheet metal from which any accumulations of moisture may drop into the drip trays 16.

15 The adjacent ends of the drip trays are spaced apart below the arms of the cross so as to form passages *q* on opposite sides of the midplane of the cooling room, extending from front to back and each of said trays is 20 aslant toward the midplane of the refrigerator in opposite directions.

The drain tray 19 is U-shape in plan, and is formed with two channels 27 and 27' connected at the lower end by a channel 28. One 25 end of the drain tray is provided with a projection 29, and the bifurcated end with cross bar 30; the drain tray is suspended below the drip trays 16 by means of the projection 29 resting upon hanger member 31, and the 30 member 30 hanging upon and over hanger cleat 32. Each channel of the tray 19 is arranged to receive the drip from two of the drip trays 16 suspended above the drain tray 19. Drainage from tray 19 is provided 35 by the means previously recited.

The ice rack 12 comprises parallel slats spaced apart thus allowing cooled air and drip from the melting ice to pass downward, and to fall upon the slanting surfaces of the 40 pan 11 from which the water flows to the chutes 17 and then over the skirts 26, from the edges of which it falls into the drip trays 16, and thence through drain holes 18 into the drain tray 19, and thence out as previously described.

45 Barriers 33 comprising overhanging edge strips 34 fixed horizontally on upright walls 35 extending up from the edges of the pan are spaced from the front and back walls, forming therewith flues 37 through which the warmer air may flow from the cooling room and over the barriers to the cooling chamber. A water proof strip 36 is interposed between the strips 34 and the wall member 35 to prevent drip from escaping to the outer sides of the barriers 33 and thence to the floor *f* of the cooling room 2.

The barrier is made rigid by means of the vertical braces 38 one end of each of which extends beyond the lower edge of the barrier, and horizontal braces 38' provide means for securing said barrier to the sides 39 of the member 24 by the use of bolts or screws.

60 I have thus provided means for collecting 65 and discharging the drip water from the

melting ice and have made provision for keeping the cooling room practically dry. The air circulation is as follows: The air cooled by the ice flows down toward the pan. The barriers 33 prevent lateral flow of air 70 at the middle portion and the cool air flows down through the cold air chutes or rectangular openings 17, from which level it is spread by the trays to fill the cooling room 2.

75 Provisions stored within the cooling room 2 as well as thermal radiation from the refrigerator body cause a gradual rise in the cooling room temperature and the warmer air will gradually rise along the walls *a* and *c* of the refrigerator until said warmed air 80 passes through the flues 37, and over the top of the barrier 33 into the ice box 1 as indicated by direction arrows in Fig. 6.

85 The walls, top and floor are made ready at the factory and are transported to the place of use and there assembled to form the refrigerator, the floor being first laid in place and the four walls *a*, *b*, *c*, *d*, being then erected and fastened together by lag screws *s*, inserted through the studding in one wall 90 and screwed into the studding of the joining wall at each corner.

95 After the sides are assembled and secured by the lag screws *s* the top *e* is placed on the seat *p* and rests thereon.

100 It is important that refrigerators in which meat is stored shall be kept free from deposits of effluvia from moisture carried by the circulation from the meat to the ice and back to the cooling room, and the ice rack in this refrigerator is made of a plurality of pieces so that it can be easily removed from the refrigerator for thorough cleansing, thus leaving the pan free to be thoroughly cleaned.

105 The baffle walls are easily accessible and the drip and drain trays underneath, are also easily removable for cleansing so that with proper attention the interior of the refrigerator can be kept perfectly sweet, clean and sanitary.

110 I claim:

115 1. In a refrigerator provided with insulated walls, top and bottom, and having a cooling chamber, and an ice chamber thereabove; a pan spaced from the top and from two of the walls and arranged between the ice chamber and the cooling chamber and having a rectangular border frame provided with a rim wall and with a central cross frame connected to the border frame to form therewith down draft openings; an ice rack arranged to support ice above the pan; baffle walls secured to two of the walls and extending upward from outer edges of the pan and spaced apart from the walls and top of the refrigerator to form therewith up draft flues on opposite sides of the pan; a trapped drain; drip collecting trays arranged to collect drip 120 from the down draft openings and provided with drain outlets; a drain tray below the 125

130

- drip trays and provided with a discharge outlet to discharge the collected drip into the trapped drain; said drip collecting tray being arranged aslant toward the discharge outlet. 5
2. A refrigerator having insulated walls, top and bottom, and an ice rack disposed intermediate the top and bottom and forming an ice chamber and a cooling chamber, a pan separating said chambers, said pan having openings therein, four drip trays removably suspended below said openings, and aslant toward each other air baffle walls connected to two of said side walls, a drain tray removably suspended below said drip trays and arranged to receive the drip from the drip trays, and a drain from the drain tray, said drain tray being substantially U-shaped in plan, and comprising drip receiving channels, 10 and a connecting channel, and a drain extending down from the connecting channel; the drip trays being spaced apart and the limbs of the drain tray located below the spaces between the drip trays. 15
3. In a refrigerator provided with insulated walls, top and bottom, and having a cooling chamber, and an ice chamber thereabove; a pan spaced from the top and from two of the walls and arranged between the ice chamber and the cooling chamber and having a rectangular border frame provided with a rim wall and with a central cross frame connected to the border frame to form therewith down draft openings; an ice rack 20 arranged to support ice above the pan; baffle walls connected to two of said side walls and extending upward from outer edges of the pan and spaced apart from the walls of the refrigerator to form therewith up draft flues on opposite sides of the pan; drip trays below said down draft openings, and a drain tray arranged to receive the drip from the drip trays. 25
4. In a refrigerator provided with insulated walls, top and bottom, and having a cooling chamber and an ice chamber above the cooling chamber; a pan spaced from the top and from two of the walls and arranged between the ice chamber and the cooling chamber and having a rectangular border frame provided with a rim wall and with a central cross frame connected to the border frame to form therewith down draft openings; an ice rack arranged to support ice 30 above the pan; baffle walls connected to two of said side walls and extending upward from outer edges of the pan and spaced apart from the walls of the refrigerator to form therewith up draft flues on opposite sides of the pan; drip trays below said down draft openings, and a drain tray arranged to receive the drip from the drip trays. 35
5. In a refrigerator provided with insulated walls, top and bottom, and having a cooling chamber and an ice chamber thereabove; a pan spaced from the top and from two of the walls and arranged between the ice chamber and the cooling chamber and having a rectangular border frame provided with a rim wall and with a central cross frame connected to the border frame to form therewith down draft openings; a drain tray removably suspended below said drip trays and arranged to receive and discharge the drip from the drip trays, said discharge tray being substantially U-shaped in plan, and comprising channels, and a connecting channel, and a drain 40 extending from the connecting channel. 45
6. A knockdown refrigerator having an ice chamber and a cooling chamber, a pan separating said chambers, said pan having openings depending therein; moisture collecting skirts; drip trays spaced apart and removably suspended below said openings and skirts, projections on said drip trays; supports below said pan upon which said projections are adapted to rest; a drain tray removably suspended below said drip trays and arranged to receive the drip therefrom and from the skirts; and a trapped drain extending from the drain tray, said drain tray being substantially U-shaped in plan, and comprising channels, a connecting channel, said drain tray extending below the spaces between the drip trays to baffle up-flow of air therethrough. 50
- In testimony whereof, I have hereunto set my hand at Los Angeles, California, this 15th day of December, 1925.
- ANTON N. HORNUNG.
